(57) **CLAIM**

The ornamental design for a handle for an electric toothbrush as shown and described.

DESCRIPTION

FIG. 1 is a front, right and top perspective view of a first embodiment of a handle for an electric toothbrush, showing our design.

FIG. 2 is a rear, left and bottom perspective view thereof.
FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right and top perspective view of a second embodiment of a handle for an electric toothbrush.

FIG. 10 is a front elevation view thereof, the rear thereof being substantially flat and unornamented.

FIG. 11 is a left side elevation view thereof.

FIG. 12 is a right side elevation view thereof.

FIG. 13 is a top plan view thereof; and,

FIG. 14 is a bottom plan view thereof.

The dashed broken lines depict portions of the handle for the electric toothbrush that form no part of the claimed design. The oblique surface shade lines shown in the drawings indicates a transparent surface.
